UNITED STATES PATENT OFFICE.

SAMUEL M. LANGSTON, OF WENONAH, NEW JERSEY.

SHEET STACKER.

Application filed April 26, 1922. Serial No. 556,736.

To all whom it may concern:

Be it known that I, SAMUEL M. LANGSTON, a citizen of the United States, and resident of Wenonah, in the county of Gloucester and 5 State of New Jersey, have invented certain new and useful Improvements in Sheet Stackers, of which the following is a specification.

This invention is an improvement in 10 sheet stacking mechanism of that type in which the separate sheets are delivered edge-wise in succession and each sheet is caused to slide over the previously delivered sheet to final position on the top of the stack, the 15 moving sheet being supported primarily by the stack during such sliding movement.

The main features of my invention adapt 20 the machine for stacking sheets having apertures, notches, transverse slots or slits, or other form or outline which may present 25 edge portions intermediate of the front and rear edges of the sheet, and extending substantially transversely of the general direction of travel of the sheet on the top of the 30 stack. Unless such a sheet be very stiff, an edge portion of the top sheet on the stack may curl or bend upwardly so as to form a stop or obstruction, or an edge portion of the advancing sheet may curve, bend or drop 35 downwardly in passing over an aperture or slot in the sheet beneath. With the ordinary stacking machine such an edge on either sheet may engage with an edge of the other sheet and prevent further advance of 40 the top sheet, or cause it to crumble up, or a portion to be folded over or under, or in other ways prevent proper stacking and vertical alignment of the edges.

If the sheets be delivered at high speed 45 and in rapid succession, the crumpling of one sheet may prevent the proper positioning or cause the tearing, folding or injuring of all the succeeding sheets until the machine is stopped, spoiled sheets removed, and the 50 stack straightened out. The main object of my invention is to overcome such difficulties and permit the rapid, accurate and free sliding and stacking of sheets of the character referred to. Other objects are to provide 55 improved means for delivering the separate sheets in succession to the stack and to improve other features of the machine.

Although certain features of my improved stacking mechanism are adapted for use 55 with sheets varying widely as to material, shape, size, stiffness, and other properties, I

have designed and selected for illustration a machine for receiving and stacking fiber shingle strips of that type in which one of the longer edges of the strip is provided with 60 a series of narrow slots or recesses between adjacent tabs or projections. Such shingle strips are commonly formed of felt, paper, asbestos or other similar material saturated or coated with a waterproofing material such 65 as tar, and coated on one side with sand, crushed slate or other mineral fire-resisting granular substance. The strips when laid in overlapping relation on a roof, with the notched edges lowermost and exposed, simulate 70 a series of individual shingles. In my improved machine strips of this character are delivered endwise with the notches or recesses along one of the side edges, and tabs or individual shingle portions of each strip 75 pass freely over the notches or recesses of the sheet beneath, even though the strip be very soft, and flexible at the time as a result of cutting up a freshly treated sheet which is still hot from the waterproofing composition 80 applied thereto. Certain features of the machine illustrated are not claimed herein, as they are the same as or similar to corresponding features illustrated and claimed 85 in a copending application of B. M. Fine, Serial No. 508,082, filed Oct. 17, 1921. The parts here shown are intended for use and cooperation with other parts not here shown, but which are fully disclosed in said 90 application.

In the accompanying drawings:

Fig. 1 is a side elevation, certain of the parts being shown in section, and the sheet delivering means adjacent to its lowermost 95 position.

Fig. 2 is a sectional detail similar to a portion of Fig. 1, but on a different plane, and showing the sheet delivering means in raised position.

Fig. 3 is a sectional detail similar to a portion of Fig. 2.

Fig. 4 is a plan view of a sheet or plurality of sheets which may be stacked by means of my improved machine.

Fig. 5 is a plan view of a stack support 105 for sheets of the form shown in Fig. 4.

Fig. 6 is a perspective view of a portion of the sheet support and sheet thereon, and

Fig. 7 is a perspective view of a portion 110 of the sheet support.

In the machine illustrated the sheets to be stacked are delivered on a wide belt or

series of narrow belts 10 extending over a pulley 11 which forms one of a pair of feed rolls, the upper roll 12 being geared to the lower one as indicated in dotted lines in Fig. 2, so that the two rollers have the same surface speed. The sheets as they are delivered from between the feed rolls or sheet delivering means 11, 12, pass onto a stack support 13 or on to the top of the stack. This stack support will be described more fully hereinafter. In order that the sheet delivering means may maintain the desired relationship to the top of the stack, irrespective of the height of the stack, means are provided for varying the relative elevation of the sheet delivering means and the stack support during the operation of the machine, and at the desired rate. As shown the sheet delivering means is mounted on a carriage 14 mounted for vertical movement on the frame 15 of the machine. The carriage carries a transversely extending shaft 16 having pinions 17 at opposite ends thereof meshing with stationary rack bar 18 on the frame of the machine so that tilting or irregular vertical movement of the opposite ends of the carriage is prevented. The carriage at its lower end is provided with a roller 19 engaging with a cam 20 on a shaft 21. This cam is of such shape and size, and the shaft 21 is driven at such speed in respect to the rate of delivery of the sheets, that the carriage raises an amount substantially equal to the thickness of the sheet in time intervals corresponding to the time of delivery of the successive sheets. Thus the sheet delivering means maintains a constant relationship to the top of the stack. When the sheet delivering means reaches its maximum elevation and the stack has been built to the desired height, the delivery of sheets to this stacking mechanism may be interrupted while the stack is removed and the sheet delivering means lowered to begin the building up of a new stack. For maintaining the belt 10 taut during the vertical movement of the sheet delivering means, there is preferably provided a belt tightening pulley or series of pulleys 22 mounted on a lever arm 23 which is pivoted on a rearward extension of the carriage. The opposite end of the lever arm is connected to the lower portion of the carriage by a coil spring 24, the tension of which may be varied or adjusted at will. As the spring is connected to the carriage, it will be noted that the belt tightener operates with equal efficiency irrespective of variation in the vertical position of the carriage.

The feed roll or pulley 11 is preferably positively driven instead of being rotated merely by the belt. The shaft of the roll is shown as provided with a miter gear 25 mounted in a casing on the carriage, and meshing with a second miter gear 26 jour-

naled in the carriage and held against longitudinal movement in respect thereto. For rotating the gear 26 I provide a vertical shaft 27 which is keyed to the gear 26 so that the latter may slide vertically on the shaft during the up and down movement of the carriage, but power will be properly transmitted to the feed roll in all positions of the carriage. The shaft 26 is illustrated as being driven from a shaft 28 through a pair of miter gears 29. The feed roll 27 is so mounted in respect to the feed roll 11 that the common line of tangency is inclined downwardly toward the stack support or the top of the stack. In other words, the axis of the upper roll is laterally displaced in respect to the axis of the lower roll, as shown particularly in Fig. 2. Thus each sheet is directed downwardly against the top of the stack at a comparatively slight angle, and is caused to frictionally engage with or bear upon the top sheet of the stack while moving to final position.

The stack support 13 is preferably in the form of a board or platform mounted on a series of rollers 30 having their axes extending in the direction of travel of the sheets. Thus the stack support may be moved laterally with the entire stack thereon, and a new stack support placed in position in a comparatively short time. The rollers are journaled on a frame 31 which has an upwardly extending arm 32 carrying a depending stop 33 adjustable toward and from the sheet delivering means. This stop may be so positioned as to insure proper placing of the stack support 13, and to limit the movement of the sheets, and define their final position. By reason of the slightly downward angle of delivery of the sheets on to the stack, a sufficient friction or resistance is offered so that as the sheets reach the stop 33 they come to rest without rebounding, and without crumpling or marring the edges against the stop.

Although some of the features above referred to involve features of my invention, the main feature of the construction is the stack support, and the other features may vary widely in details and arrangement of parts. In the construction illustrated the stack support is intended for use with fiber shingle strips of the character shown in Fig. 4. Each strip includes a body portion A provided with a series of recesses, notches or slots B in one edge thereof, so as to form tabs or projections C. These are of a width and length so that when the strips are laid in proper overlapping relationship with the tabs or projections exposed at the lower edge, they will create the appearance of individual shingles. My improved machine is especially adapted for the stacking of strips of this kind where the strips are delivered endwise, that is, where the slits and

projections extend in a general direction substantially at right angles to the direction of delivery of the sheets or strips. Any desired number of these shingle strips may 5 be formed simultaneously in the machine, and delivered edge to edge at the same time, one such arrangement being that shown in Fig. 4, where each sheet or section of the roofing material includes three separate 10 shingle strips cut and formed simultaneously from the prepared material. These strips are shown as having the slots of two of the sheets opposed, so as to form the openings D, each of a length equal to twice 15 the length of the slot in an individual shingle strip, and the third shingle strip has its slots terminating at a straight edge of the middle strip. Obviously a greater or lesser number of strips may be simultaneously delivered, 20 and the slots may be in various different relationships, so far as positioning is concerned. Also, the slots and tabs may be of other forms, and the machine may be used for stacking strips of material other than 25 shingle strips, and which have the edges extending substantially transversely of the general direction of delivery of the sheet, and which may abut to interfere with free sliding movement of the sheet.

30 For stacking the specific arrangement of shingle strips shown in Fig. 4, I provide the support 13 with a series of cam projections 35, as shown in Fig. 5. Each projection has a substantially vertical surface 36, so positioned as to register with a slot of the 40 sheet, and of a length substantially equal to said slot. From this vertical surface the upper surface 37 of the projection is inclined downwardly and merges into the upper 45 surface of the body portion of the stack support. The high point of the projection is so positioned that it comes at the far or outer corner of a corresponding tab or projection on the sheet, and the upper surface 50 from this high point is inclined downwardly both toward the body of the sheet and toward the sheet delivery means. If the projection or raised part of the stack support 55 is for cooperating with a single tab or projection of the sheet, the projection may have a vertical surface extending in the direction of delivery of the sheet and registering with a side edge of the sheet, as shown at the 60 lower portion of Fig. 5. If one projection or raised portion is to support oppositely 65 facing tabs of two different sheets, this projection of the stack support may correspond in size and shape to two of the projections 70 as shown at 35^a in Figs. 5, 6 and 7. This 75 form has its upper surface inclined downwardly in opposite directions from the center line which registers with the dividing line between two sheets.

From Figs. 3 and 6 it will be noted that 80 each sheet when in final position has the

opposite edges of each slot vertically displaced relatively to each other, that is, the side of the slot farthest from the sheet delivering means lies in the plane of the body of the sheet, while the side of the slot nearest to the delivering means is raised to a height slightly greater than the thickness of the sheet. In other words, each laterally extending tab or projection of the sheet, with the exception of the one farthest from the sheet delivering means, has its far edge raised so that the next sheet in being delivered to the top of the stack, will be guided across the slots in the top sheet of the stack without liability of catching on the edge of 80 the slot. The projections of the stack support will raise the proper portions of the first sheet delivered, and this raising effect will be repeated up through the entire stack, as shown particularly in Fig. 2. As the 85 sheet delivering means and the stack support are moved vertically relatively to each other, the sheet delivery means maintains constant relationship to the top of the stack, and the top sheet of the stack always has 90 portions thereof raised in the same way as has the stack support itself. Thus, the sheets may be delivered at high speed and in rapid succession, and each sheet will have its tabs guided across the slots in the preceding sheet without liability of catching, 95 crumpling, tearing, or displacing.

Having thus described my invention, what I claim as new and desire to secure by Letters Patent is:—

1. A machine for stacking slotted sheets, including means for delivering the sheets edgewise in succession in a direction at an angle to the general direction of the slot, and a stack support having means for holding the portion at the near side of the slot at higher elevation than the portion at the far side of the slot.

2. A machine for stacking slotted sheets, including means for delivering the sheets edgewise in succession in a direction at an angle to the general direction of the slot, and a stack support having a portion raised above the general plane of the support for registering with the portion of each sheet 115 at the side of the slot nearer to said delivery means when the sheet is in final position.

3. A machine for stacking slotted sheets, including means for delivering the sheets edgewise in succession in a direction at an angle to the general direction of the slot, a stack support having a projection for supporting the portion of each sheet at the side of the slot nearer to said delivery means at a higher elevation than the portion at 125 the opposite side of the slot when the sheets are in final position.

4. A machine for stacking shingle strips having a series of spaced tabs or projections along one side edge, said machine including 130

- means for delivering the strips endwise in a substantially horizontal direction in succession, each sheet being caused to slide over the upper surface of the last previously delivered sheet on the top of the stack, and a stack support having means for holding the edge of a tab or projection which is farthest from the delivery means at a higher elevation than the edge of the same tab or 10 projection nearest to the delivery means.
5. A machine for stacking shingle strips having a series of spaced tabs or projections along one edge thereof, said machine including a stack support having a projection 15 on the upper surface thereof for holding in upwardly tilting position a corner portion of certain of the tabs or projections of the shingle strip.
6. A machine for stacking slotted sheets, 20 including means for delivering the sheets edgewise in succession in a direction at an angle to the general direction of the slot, a stack support having a projection on the upper surface thereof, the edge of the projection farthest from the delivery means registering with the slot of the sheet when the latter is in final position, and the upper surface of the projection between said edge and said delivery means being inclined upwardly from the surface of the support to 25 said edge.
7. A stack support for shingle strips having a series of projections each of a length substantially equal to the length of the corresponding slots in the shingle strips and having a substantially vertical face registering with the slot and an upper face inclined upwardly to said vertical face at a comparatively small angle.
- 30 8. A machine for stacking a plurality of simultaneously delivered shingle strips each having laterally facing projections or tabs, said machine including a sheet delivering means and a stack support, said support having means for holding in an upwardly tilting position the outer corners farthest from the delivery means of each of the shingle strip projections.
- 35 9. A stack support for shingle strips including a supporting board or platform and a projection thereon, said projection having a substantially vertical edge for registering with the slot between adjacent tabs of the shingle strip and a vertical edge for registering with the side edge of the strip, the upper surface of the projection between said vertical edges being inclined downwardly and merging into the upper surface of the 40 support.
- 50 10. A stack support for shingle strips including a supporting board or platform and a projection thereon, said projection having a substantially vertical edge for registry with the opposed slots of two adjacent shingle strips, said vertical surface being substantially triangular, and an upper surface inclined downwardly from said vertical edge and merging into the upper surface of the board or platform.
- 55 11. A machine for stacking slotted sheets, including means for delivering the sheets edgewise in succession in a direction at an angle to the general direction of the slot, a stack support having means for holding the portion at the inner side of the slot at higher elevation than the portion at the far side of the slot, and means for varying the relative elevation of the sheet delivering means and said stack support to maintain substantially constant relationship of said delivery means and the top of the stack.
- 60 12. A machine for stacking slotted sheets, including means for delivering the sheets edgewise in succession in a direction at an angle to the general direction of the slot, and a stack support having means for holding the portion at the inner side of the slot at a higher elevation than the portion at the far side of the slot, and means for raising 65 said sheet delivery means at a rate corresponding to the rate of increase in the height of the stack so as to maintain substantially constant relationship of said sheet feeding means to the top of the stack.
- 65 13. A machine for stacking slotted sheets, including means for delivering the sheets edgewise in succession in a direction at an angle to the general direction of the slot, and a stack support having means for holding the portion at the inner side of the slot at higher elevation than the portion at the far side of the slot, said sheet delivering means including a pair of rollers having 70 their common line of tangency inclined downwardly toward said stack support.
- 70 14. A machine for stacking slotted sheets, including means for delivering the sheets edgewise in succession in a direction at an angle to the general direction of the slot, a stack support, and means for varying the relative elevation of the sheet delivering means and said stack support to maintain substantially constant relationship of said delivery means and the top of the stack, said sheet delivering means including a pair of rollers having their common line of tangency inclined downwardly toward said stack support.
- 75 15. Signed at New York in the county of New York and State of New York this 17th day of April, A. D. 1922.
- 80 16. SAMUEL M. LANGSTON.
